UNITED STATES PATENT OFFICE

EDWARD F. RAU, OF BROOKLYN, NEW YORK

COLLAPSIBLE FURNITURE CRATE

Application filed January 6, 1928. Serial No. 244,808.

This invention relates to improvements in collapsible or knock-down crates, primarily designed for shipping purposes, wherein furniture of various kinds and forms may safely be packed and transported, whereupon the empty crates may be taken apart and packed in compact bundles, to be returned to the shipper for future use. As the freight rates for these knocked down crates, occupying but little space in the car, are a comparatively low item, this system results in a great saving not only of material and cost of labor but also of time, and furthermore offers greater convenience and efficiency in handling shipments.

This invention aims especially at various improvements of the construction of a similar furniture crate for which a U. S. patent was granted to the applicant on June 21, 1927, under Number 1,633,354, and while therefor the different general objects of this invention are in the main identical with those of its prototype, there are nevertheless certain conditions for which this simplified form of a crate is better adapted. A further saving in manufacturing costs is effected by a simplification and standardizing of parts.

The primary specific object therefor is to procure a skeleton box crate of the collapsible type, which combines with a minimum of material great rigidity and ability to withstand rough handling.

Another object is to make the structural members of the simplest form, reduce their variety to but a few items and make them as interchangeable as possible.

A third object is to simplify the mechanism and make the combination so easy and fool-proof that any unskilled help is able to assemble or take apart the crate without explicit directions or previous training.

Other objects in compass with and following from the above noted objects will become evident from the present description.

One of the main objects of the forerunner of this invention, as mentioned above, was to construct a box crate, adjustable in all directions, so that it could be enlarged or contracted in all or any of its three main dimensions. While this facility is desirable,

where a variety of goods to be shipped is considered, there are instances where only standard articles of one and the same kind and size are to be crated. In such case this feature of adjustability is evidently superfluous and involves unnecessary expense and complication. One or a few different sizes of suitable crates of definite volume are apparently preferably to meet this condition. The present crate therefor, as shown in its preferred form, lacks the feature of adjustability as to volume. That however the exact new principles of construction can, with slight modification, be also extended and adapted to adjustable crates of the formerly described class, will be shown and illustrated hereafter, and the scope of the claimed invention consequently covers this class of collapsible crates also.

The former invention also showed adjustable means whereby the furniture inside the crate might be secured or suspended, so as to be held stationary and be kept clear from contact or impact from the outside. This feature is retained in the novel construction, though the means of achieving this purpose differ and are attained by a rearrangement and novel application of parts, already utilized in the outer construction of the crate.

With all these objects and modifications in view the invention consists in the construction, combination and arrangement of parts hereinafter described and claimed, and illustrated in the accompanying drawing in which:

Figure 1 is a perspective view of a crate, embodying the principles of this invention, and shown in assembled form.

Figure 2 is a perspective view of the typical iron clasp or clamp for connecting two sections of the frame.

Figure 3 shows a modification of this clasp which may be used either instead of or in connection with the first form shown.

Figure 4 indicates an alternate form of this modified clasp, necessary for certain conditions.

Figures 5 and 6 show the plan and the side view respectively of a typical frame member of an extensible crate, built on the same gen-

eral principle as the one shown in Figure 1. Figure 7 is a top view of a clasp, used as a clamping iron on an interior suspension member of the frame.

5 The same or similar reference characters denote the same or similar elements throughout the different views.

Concerning the construction in detail it will be observed that the crate, presenting the 10 customary skeleton form, is primarily composed of solid wooden beams or slats of rectangular cross section. In general they will be only of three different lengths for each 15 particular crate, as may be verified by inspecting Figure 1, members of opposite or parallel sides being of the same length. The interior or suspension members also fit into this classification, being parallel to the bottom or side members. This is an obvious 20 advantage for the purpose of assembling or packing the knocked-down crate in bundles.

The iron parts, used for erecting the crate, are also more or less uniform, consisting of a 25 number of slotted clasps of angular shape, all more or less alike, which can neatly be tied in solid packages, and a number of simple bolts, nuts or washers, just as easily tied together or strung on cords.

A further apparent advantage of this 30 standardization and simplification of component parts is that in case of emergency, for instance, if parts of the crate are lost or broken, a substitute is easily found or provided and that changes or modifications in 35 the location of members, necessitated by the contents to be crated, may quickly be effected through the drilling of a few additional holes in the timber.

Referring to the drawing in particular, 40 numerals 11, 12 and 13, indexed "a" or "b", designate the slats, forming the panels of the crate, equal numbers indicating equal length dimensions. The edge members are named 11^a, 12^a and 13^a, while 11^b, 12^b or 13^b refer to 45 the middle braces. They consist of wooden beams of rectangular cross section, preferably flattened, and provided with the necessary bolt holes for the connecting clasps. These holes are drilled either a suitable short dis- 50 tance from the extreme ends, as 14^a for the corner clasps 20, or, like 14^b at suitable equal intervals throughout the length of the slats, for the fastening of similar clasps, which hold the middle braces 11^b, 12^b and 13^b in position.

55 Where cross braces 16 are used across the inner space of the crate, as supporting means for the secure free suspension of furniture, as before mentioned, holes 16^a are suitably provided for bolting on the clasps 20, which 60 in turn keep the braces 16 in their proper place by means of through-bolts 22. Simultaneously these through-bolts serve as means to clamp down the slidably arranged upturned clasps 21 which are intended to grip the suspended furniture sidewise and hold it firmly

in place, while at the same time the wooden braces 16 serve as supports for it. In the drawing many of the bolts are left out and only the holes for them indicated.

In the case that the location of the cross 70 braces is not permanently determined for a certain staple article for which the crate is intended, a wide range of adjustability can be provided by drilling a series of holes 16^b through the panel slots supporting the interior cross braces 16. 75

The clasps 20, a typical sample of which is shown in Figure 2, consist of two parallel flat bars, 20^a, lying in the same plane and leaving a slot 20^a between them, wide enough to pass the bolts 22 through. About in the middle these two bars are bent at right angles and at the extreme ends they are joined by short flat cross bars 20^b. These cross bars may be separate pieces welded or riveted on, 80 as shown at 20^c or the whole combination, which as described, resembles a flat gridiron, bent over into a bracket form, may originally be punched out of one solid plate. 85

A modification of this preferred form of 90 clasp is shown in the clasp 23, Figure 3, and it consists in letting the parallel main bars end in two sharp prongs, 23^a, protruding beyond the end cross bar and bent over at right 95 angle in the same sense, as the bend in the middle of the flats is made. This modification is applied to one pair of legs of the clasp only, while the end of the other pair of legs is shaped as described before. These prongs take the place of one of the fastening bolts 100 and can advantageously be used, where a protruding bolt head or nut would be in the way or inconvenient, for instance at the bottom of the crate or underneath the slidable interior clasps 21, holding the furniture. As 105 these prongs can easily be driven into the wood, when they run parallel to the grain, but with difficulty across it, it is obviously of advantage in some cases to form these prongs out of the ends of the cross bars, as 110 shown at 23^b, Figure 4, so as to fit the run of the grain. 115

While it will be found quite feasible to 120 make all the clasps, even the interior clamping members 21, after one pattern only, it may be necessary, especially for the clasps underlying those, marked 21, to extend one pair of legs, or even have clasps of different sizes.

The clasps 21, if they are not intended to 125 be stationary, in which case they may be provided with prongs, similar to those shown in Figure 4, only turned downward-facing the timber—should, if adjustable and bolted, be so formed that the head of the bolt or the nut could eventually pass through the slot of the upright leg. This can be effected, as 130 Figure 7 shows, by making the slot width of the upright leg sufficiently wide (20°) for the bolt head to pass through, while on the hori-

zontal legs, fastened to the beam the slot tapers down to the normal width 20⁴.

The reason, why the clasps are formed as slotted brackets and not as simple angle plates, perforated for the bolts, is that in the first place the crate beams, being manufactured as cheaply as possible, are not likely to be of accurate fit and workmanship; in the second place the slots serve as a sort of shock absorbers in the case of violent handling or throwing about of the crates. It has been found that in case of too rigid connections which allow no play for the bolts or crate members, the shock or concussion is transferred with full force to the contents and, for instance, in the case of mahogany furniture, easily causes cracks and peeling off on the veneers. With a crate construction, as shown however, a shock is gradually and partially absorbed through the many slotted connections, which, though with tightened bolts ordinarily rigid, will give enough under the force of impact to permit a momentary re-adjustment without jarring the whole contents too much.

Corner connections of three converging beams are easily formed, by the ends of three clasps overlapping each other, each bolt passing through one beam and two clasps on each panel side, as the illustration of Figure 1 shows.

Finally, if instead of using single crate beams of definite length, these beams, in each case, are composed of two halves 25, perforated at intervals, as shown at 28, partly overlapping each other in the middle and held in slidable connection by a saddle plate 26, through which a through-bolt 27 passes, adapted to firmly clamp the two halves together, it is apparent, that with this slight addition, the crate is converted into an extensible crate, similar in its application to the one described in Patent Number 1,633,354.

Various minor changes in the form, proportion and details of construction may be made without departing from the general principle of the invention, and its scope has therefore to be judged not so much according to the drawings as to what is claimed as novel.

Having thus described my invention, what I claim as new and desire to secure by Letters Patent, is:—

1. A collapsible shipping crate, formed of three sets of uniform rectangular beams, fitted respectively with their ends at right angles to each other, so as to form a rectangular skeleton box frame, a plurality of clasps, formed of flat bars, slotted lengthwise and bent into right angle irons, adapted to form lap joints over said beams, and means to bolt the clasps to said beams.

2. A collapsible shipping crate, formed of exterior rectangular beams of solid cross section, forming three sets, differing in lengths, of relatively interchangeable beams, a plu-

rality of interior supports, formed of similar rectangular beams of solid cross section, interchangeable with each other and with the exterior parallel beams, said supports being adapted to hold objects crated in fixed position, and connecting means, consisting of slotted rectangular brackets of the same pattern, interchangeable with each other and adapted to rigidly fasten said beams and supports at right angles to each other, forming thus all lateral and corner connections for exterior and interior beams.

3. A collapsible crate, formed of a plurality of rectangular slats, a plurality of slotted clasps, bent at right angles so as to form connecting brackets between said slats, adapted to serve as lateral edge connections as well as corner bonds, and means cooperating with said clasps, to fasten said slats together to form a skeleton box frame, substantially as shown and described.

4. The combination with a collapsible furniture crate, consisting of a plurality of rectangular slats, fitted with their ends at right angles to each other so as to form a skeleton box frame; of a plurality of connecting clasps formed of flat bars, joined together so as to form a grid, bent at right angles into bracket form, slotted lengthwise and adapted thus to be adjustably bolted over the butt ends of said slats and to serve as shock absorbing semi-rigid connections for said box frame.

5. The combination with a collapsible furniture crate, consisting of a plurality of rectangular wooden slats, fitted together so as to form a skeleton box frame; of a plurality of connecting clasps, formed of flat bars, joined together so as to form a slotted grid, bent at right angles into a bracket, adapted to be bolted adjustably over the butt ends and edges of said rectangular slats, and means to fasten said brackets rigidly into the grain of said wooden slats, substantially as specified.

6. A collapsible box crate, formed of a plurality of rectangular solid slats and adjustable means, interchangeable with each other, to fasten the outer ends of said slats at right angles to each other and to the side edges of other slats, so as to form a skeleton box frame, said means consisting of a plurality of slotted clasps interchangeable with each other, overlapping the butt ends and edges of said slats and adapted to be adjustably bolted to them to form all lateral and corner connections.

7. In a collapsible box crate the combination with a plurality of uniform rectangular beams of solid cross section, forming three sets differing in lengths and being interchangeable with each other within the same set respectively; of a plurality of uniform slotted clasps, interchangeable with each other and adapted to be bolted to said beams

and to fasten them at right angles to each other so as to form the edges and corners of the box crate.

In testimony whereof, I have signed my name to this specification in the presence of two subscribing witnesses, this third day of January, 1928.

EDWARD F. RAU.
